GYROSCOPE MOTOR

Jones Nogueira Carvalho, Rio de Janeiro, Brazil

Application September 8, 1958, Serial No. 759,762

Claims priority, application Brazil April 28, 1954

1 Claim. (Cl. 123—18)

This invention relates to an internal combustion engine operating on the principle of a gyroscope, and is a continuation in part of my application Serial No. 498,003, filed March 30, 1955.

An object of the invention is to obtain greater horsepower with less fuel consumption and less total weight for the motor assembly as compared with present day conventional motors. These results are obtained by better use of the expanded gases detonated within long stroke cylinders independently of the diameter thereof by means of an improved combined lever and piston rod.

Another object is to provide a motor assembly wherefrom the use of the power action and also the motor reaction can be made.

The drawings diagrammatically illustrate the invention as follows:

Figure 1 is a vertical sectional view of the improved motor taken on the line 1—1 of Figure 2.

Figure 2 is a horizontal cross sectional view taken on line 2—2 of Figure 1.

Figure 3 is a detail view of the expandable cam means for operating the intake valves.

Figure 4 is a top plan view of the cam plates shown in Figure 3.

Figure 5 is an exploded perspective view of the cam shaft whose upper portion has the expandable cam elements thereon and whose lower portion has the fixed cam for operating the exhaust valves.

Figure 6 is a detail perspective of the expandable cam assembly.

Figure 7 is an enlarged vertical sectional view of the gas inlet means, distributor, and governor means for controlling the expandable cam means.

Similar reference characters designate like parts in the several views.

As will be apparent from the drawings, the present motor differs from conventional motors in form or shape as it appears when viewed in a horizontal plane. For example, as shown in Figure 1, the motor assembly includes a housing or chassis 1 having the general characteristics of a flattened sphere and concealing therein a motor 2 resembling a flywheel rotatable about a central shaft 9 supported in a gear box.

The housing or chassis is stationary and supports the generator, the starter, the induction coil, carburetor, lubricant intake means and other essential accessories. The motor may operate as a two or four cycle engine and conventional ignition and carburetion systems may be used.

Referring more particularly to the Figures 1 and 2, the stationary housing or chassis designated generally as 1 is mounted by suitable supports A on an appropriate part of a frame, or automotive chassis or the like, to remain stationary throughout its use.

The motor or engine is designated generally by its 70 casing 2 within the housing. The motor includes the opposite upper and lower walls 3 and 4 spaced internally

2

to receive piston actuating means, as will presently appear. The peripheral portions of the casing 2 are provided with the cylinders 5, 5 which receive the pistons 6, 6. The cylinders 5, as will be apparent from Figure 2, are located at substantially diametrically opposite positions in the body of the engine casing 2.

The pistons for opposite cylinders are rigidly and fixedly connected by a one-piece, Z-shaped lever including the piston rod portions 7 and the shank portions 8 extending diametrically across the vertical axis of the motor and operating about the central or primary shaft 9. The upper end of this shaft is provided with an internal axial bore 9a and a vertical slot 9b on one side. It performs several functions such as; operating the distributor; acting as a cam shaft; as well as to actuate cams respectively for the intake and exhaust valves; and to provide a lubricant lead in.

The shank portions 8 of the Z-shaped lever are connected by links 10 with the medial portions of the crank shafts 11. The arm portions 12 of each crank shaft are journaled in the upper and lower walls 3 and 4 of the motor and one arm of each crank shaft has a pinion 13 keyed thereto. This pinion in turn meshes with a primary gear 14 mounted coaxially with and keyed to the primary shaft 9 and within the housing 2 of the motor adjacent and below the shank portion of the lever. The piston lever 7—8 is free to turn relative to the shaft 9.

An expandable cam C surrounding the upper portion of shaft 9 alternately operates the lever arms 16 for actuating the intake valves 17 in each cylinder. A rigid cam C' on shaft 9 actuates the levers 18 for exhaust valves (not shown).

The cam C has two motions, one rotating motion given by the primary shaft 9 and one vertical motion given by the governor designated generally as G and later to be described in more detail.

As previously indicated, because the shaft is hollow, it has therein a stem 20 axially movable relative to the shaft, and which stem through the governor controls the cam C. This cam is substantially conical in shape and is made up of several metal plates C², C³, C⁴, C⁵, C⁶, C⁷, to obtain the desired expandable effect of the cam. Each plate is provided with a round hole C⁹ to fit over shaft 9. The plates of cam C are operated by two keys, namely, the key 21, which is a projection on the stem 20 and moves therewith to elevate all of the plates, and the key 22, which is disposed at the side of the shaft 9 opposite to the first key and is secured to the shaft 9 at an angle of approximately 20°. Half of the plates forming the expandable cam are connected to the projection or key 20 and the other half of the plates are guided by key 22.

When the governor G lifts the cam C through stem 20, alternate plates project outwardly, each from between the others, due to the angled key 22. Under these circumstances, the plates make the cam expandable to provide a peripheral surface of increased curvature at the desired moment in the intake phase of the motor depending on the speed of rotation of the gyroscope motor. The levers 16 are thus actuated to control the suction valves.

The exhaust valve cam C' does not have such details for operation. It is simple and rigid, and located on the primary shaft 9 as shown in Figure 1.

The object of the expandable cam is to regulate the degree and time of opening of the intake valves to maintain proper compression within the cylinders at various speeds. Only cylinders of the type shown need this type of intake valve cam and that is why the expandable eccentric or cam is considered a characteristic of the invention.

As will be seen from Figure 1 and the enlarged detail view, Fig. 7, the upper wall of the housing 1 of the motor is provided with a cage D which protects the gas supply

means, the governor G, timing and ignition device, as well as the means for supplying lubricant to the motor.

Referring further to the hollow stem 20, whose lower end extends into bore 9a of the shaft 9, it will be seen from Fig. 7 that the upper portion of the stem is rotatably supported by nut 24 on a ball race 25 housed within a sleeve 26 held non-rotatably to the shell of the dome D by a bracket 27 and compression scale arm 28. The top of the sleeve 26 is provided with a lubricant inlet nozzle element 29. These elements 25-29 are all under the influence of a compression spring 30 whose upper end abuts against the plug 31 in the top of the dome D. Thus, the lubricant nipple 29 may be connected with any suitable external source of supply, and, because of the hollow passage therein which is coaxially disposed with the axis of the hollow stem 20, lubricant may be supplied through the stem 20 and a slot 9a of primary shaft 9 for distribution by centrifugal force to the gears 13, 14, and their bearings.

The non-rotatable annular casing which supports the stem 20 through nut 24 and ball race 25 may, because of the arrangement described, have relatively slight axial movement cushioned by spring 30; nevertheless the casing itself does not rotate, while on the other hand the stem 20 which is interlocked with the upper end of the shaft 9 may turn freely within the casing. The spring 30 also serves to restrain overtravel of the governor G.

The distributor plate 32 is mounted coaxially with the sleeve 26 and the stem 20. This distribution plate is made of insulating material with customary metal contacts and carries at its underside a cam 33 which lifts the contact point of the primary breaker (not shown) but mounted in the customary manner on the pin 34. Since the sleeve 26 is non-rotatable, the same may be conveniently provided with a terminal block 26a for the ignition wires 26b.

The sleeve 26 and distributor 32 are surrounded by a collar 35 of insulating material such as ebonite. The collar 35 is carried by the rotatable hub 36 having slots 37 in the sides thereof to admit the tips 38 of the governor lever arms 39 pivoted as at 39a to bracket 40 on hub 36, said lever arms in turn carrying the usual weights 41.

The tips 38 of the lever arms 39 of the governor G engage beneath the outer annular flange 42 of a support S whose inner annular flange 43 houses ball race units and supports distributor elements 32, 33, 34, etc. The said support S is held on elongated bushing 44 by nut 45 which bushing surrounds stem 20 and rotates relative thereto but in the opposite direction. The upper end of the bushing supports the ball race 25, which in turn supports nut 24 carried by the upper end of stem 20. It will thus be seen that when governor action causes support S to move up or down, the stem 20 which controls the cam C will move correspondingly.

Moreover, it will be seen that the hub 36 is formed with a reduced lower threaded end portion 46, in turn connected with a sleeve 47 which rotates with the top wall 3 of the motor in the direction opposite to that of the stem 20. As will be seen from Fig. 7, the lower end 48 of sleeve 47 is fastened to the wall 3 of the motor and houses a ball race 49 which receives the upper end of the primary shaft 9.

As the motor casing including the wall 3 rotates, sleeve 47 and hub 36, 46 will also rotate and the weights 41 will move outwardly by centrifugal force. The inner ends of the levers 38 engage beneath the outer flange 42 of the support S, which carries the breaker represented by pin 34 and which breaker is free to rotate with the insulating collar 35 so that as the motor speed picks up, the tips 38 of the governor arms may lift 42-43 and in turn elevate the stem 20 so that the expandable intake valve cam C will be operated.

The fixed distributor wires leading from terminal 26a are encased in a cable 56 having vapor tight covering and

are led through 36 and 46 to and within the sealed tight conduit 47, 51-52, thereby turning with sleeve 47, which in turn rotates with the top wall 3 of the motor. The battery and coil for the ignition system are located 5 outside the engine assembly and the coil wires 26b are connected to terminal 26a. As usual, one wire is grounded to the frame and the other to the brush 36a, which bears on collector ring 36b. This collector is conductively connected in a conventional way with the 10 breaker represented by pin 34.

The sleeve 47 is externally provided with a cam 50 for operating a gasoline pump (not shown) and is internally provided with means forming a vaporized gas conduit, including the tubular central wall 51 and top sealing disc 52 communicating with an intake port 53. This port in turn communicates with the fixed ports 54 of a vaporized fuel duct 55 having inlet 56 on a tubular element 57 fixed to the motor housing 1. A carburetor (not shown) is attached at the inlet 56. It will thus be seen 20 as the motor casing including the top wall 3 rotates, gas may be fed from the conduit means 51, 52, 53 into the intake manifold 55 whose outlet ends are secured to the cylinders 5 to establish communication with the intake valves 17.

The bottom wall 4 of the engine of the motor casing 1 is provided with a hub 60 which is rotatable in the bearing 61 in the lower wall of the housing 1. This hub 60 is provided with a bevel gear 62 which in turn meshes with a gear 63 carried by a first shaft 64 suitably journaled in one side of the gear box 65.

The vertical or primary shaft 9 extends through the hub 60 and is provided with a gear 66 which in turn engages gear 67 on a second shaft 68 rotatably journaled in the side wall 69 of the gear box 65 opposite the wall 35 in which the shaft 64 is journaled.

The peripheral portion of the housing 1 is provided with a plurality of outlets or openings 70 which collect the exhaust gases and conduct them to atmosphere.

It will be understood that the valves 17 or conventional and, therefore, only diagrammatically illustrate the intake and exhaust of fuel and spent gases. Fuel may be supplied through the manifold 55 connected to the inlet 54. Also, the spent gases are conducted from each cylinder to the channel 70 of the exhaust collector ring by the 40 exhaust pipes 71, and led to the atmosphere by the outlet pipes 72 of which there may be more than the one shown.

The general operation may be described as follows:

The outer stationary parts are housing 1; cage D; gear box 63. The tubular element 53 is fixed to housing 1 50 and has the carburetor connection 54.

The parts rotating in one direction are essentially the motor casing 2 and all of its associated parts, including sleeve 47 and its conduit forming means 47a, 47b and manifold 55 which are carried by top wall 3 of the motor 55 casing. The sleeve 47 also carries with it the parts 33-43 inclusive which include the governor G.

The parts turning in the opposite direction include primary shaft 9 interlocked with tube 20 and the rotor 32 of the distributor.

The rotary casing 2 is mounted in housing 1 supported at points A-B on the chassis and is free to rotate in either direction.

If the housing 1 is mounted on an automotive chassis, the motor 2 rotates within the housing and in so doing 65 will tend to turn the gear 67 which through gear 66 is connected to the central shaft 9 carrying gear 14. While the vehicle remains stationary, these parts do not turn. However, when the casing 2 is turning, it carries with it the pinions 13 causing them to turn about the gear 14 70 which is keyed to the primary shaft 9. As the pinions 13 turn, they carry with them the crank shafts 11 and cause the reciprocating movement of the pistons relative to their cylinders.

Z-shaped element 7-8 is mounted on the central shaft

9 but is not fastened to it. When the motor is running, the flywheel-like casing 2 turns to the right, that is clockwise, while the central shaft 9 turns to the left, or counter-clockwise, but owing to the braking effect of the transmission gears mounted in the housing 65, the axles 64 and 68 turn in the same direction. In order to normalize the operation of the vehicle, the clutch of the transmission must be placed between the shaft 64 and the wheel of the vehicle.

In operation, the motor is braked exclusively by the shaft 68, but, as the vehicle runs, and due to the fact that the braking effect is transformed into tangential force, rotation of the casing 2 is gradually slowed down as much as 55%, thus decreasing the action of the centrifugal force without, however, decreasing the power of the explosions in the cylinders. As a consequence it will be seen that the braking effect will be achieved by means of the shaft 68. It is obtained in the friction produced by one of the wheels of the vehicle connected to the shaft 68 in contact with the ground. Therefore, the engine 2 has a stay or an anchor point outside of the moving body.

In the operation of the gyroscope of the engine as a whole, it will be seen that the lever 7-8 or the piston 6 does not have a reciprocating motion in the sense of the usual internal combustion engine, but they do have a steady semi-alternating rotation. For example, if a marker is placed outside the gyroscope engine solely for measuring or indicating the movement and position of the pistons, and the gyroscope engine is made to turn slowly, it will be seen that the pistons do not return to the point of the marker. Thus, they do not have a reciprocating movement with respect to a dead center in relation to the marker, but do have a faster or slower progressive movement depending on the speed of rotation of the casing 2. In the present gyroscope engine the lever 7-8 and pistons 6 initially attain twice the angular stroke of the cylinders and then reduce their speed down to approximately $\frac{1}{4}$ of the stroke of said cylinders. It is the faster or slower oscillation of the lever that constitutes the stroke of the pistons but without having reciprocating movement on a dead center, properly speaking.

The cylinders 5 being formed within the engine casing 2, are mounted to be free to turn with the casing in either direction, and, when the casing 2 is turning, it rotates and actuates the Z-shaped lever 7-8, which movement constitutes the stroke of the pistons in the cylinders. Owing to the fact that the entire assembly is turning in the same direction in a given instance, the pistons do not reciprocate in relation to the marker, placed outside the motor solely to measure the movement of the pistons.

If the shaft 68 is allowed to rotate freely, and by appropriate means the rotary casing 2 is held stationary, the gearing assembly within the casing will turn while the casing remains stationary. Thus, the engine is capable of operation with the casing 2 in rotary motion or when the same is held stationary. The rotation of the casing 2 does not have any definite relation to the number of explosions in the cylinders 5. The speed of rotation of the casing 2 is greater or less in relation to the driving power. For this reason, pistons do not have a definite alternating or semi-alternating motion. When the engine is in normal operation, everything will be turning in the same direction.

If the gyroscope engine is adapted to an automobile, the central shaft 9 of the motor must be geared to the half axle of one of the wheels of the automobile, which wheel would then be only part of the motor to receive the impulses from the explosions of the cylinders which tend to actuate the rotating casing 2. If the wheel of the automobile in contact with the ground, and which restrains the main shaft 9, is lifted, the motor casing 2 will

not turn because it is supported in the housing 1 only by the roller bearings 61 in the fashion of an automatic flywheel because the engine 2 does not have firm support for bringing about its action. For the gyroscope motor to operate, it is essential that both driving wheels of the automobile rest on the ground.

Specific examples of the operation of the motor are as follows:

Example I.—The gyroscope motor may work with the axle 68 stationary, that is, held in a fixed position by friction or any other equivalent means. Under these conditions, the motor body 2 which is rotatably supported on the bearing 61 turns the gear 62 and consequently the gear 63 as well as its axle 64.

Example II.—Conversely, as the axle 64 is restrained, and at the same time, the other axle 68 is free and the engine is functioning, it will be seen that because the axle 64 is held motionless, the engine body 2 also remains still or motionless because it is rigid with hub 60 and gear 62 meshing with gear 63 on 64. Under these conditions the engine works internally, driving the gear 14, the central shaft 9 and the gear 66 and consequently the gear 67 as well as the axle 68.

Example III.—If the axles 64 and 68 are both free at the same time and the engine is started, it will be seen that under these conditions all of the mechanism of the motor works freely, the axles 64 and 68 turning simultaneously. The rotation and the power of each axle is great or small as the resistance is greater or smaller on the opposite side of the differential system.

As will now be seen, the present invention provides a mechanical arrangement similar to the arrangement of a conventional gyroscope. In detail, the difference is that the conventional gyroscope has a solid rotating body and central shaft, whereas the gyroscope engine now submitted has its rotating body and central shaft made up of various parts.

The vertical hoop which forms a part of the structure of the conventional gyroscope and receives the effects of the motion of the flywheel is comparatively weak, whereas, the corresponding parts designed for use in a power device must be strong. As for the horizontal hoop that completes the structure of the conventional gyroscope, it is represented in the present gyroscope engine by the chassis of the vehicle powered by the aforesaid engine. The motor device herein referred to has the same features of a gyroscope with the notable added difference that the conventional gyroscope needs to be set in motion in order to perform, while the motor device in reference has its own motive power. It is on account of this similarity of principles that the present device has been called a "gyroscope engine."

The engine has many conventional details but is characterized by three points of novelty clearly outstanding, as follows:

First, the inventor uses the physical form of a gyroscope to create in said form an engine to operate under the power action and also under the reaction. Therefore, the claim of a motor structure on the principle of a gyroscope is a novelty.

Second, the gyroscope system structure has allowed the motor reaction to be used through a second motor shaft. Therefore, the use of the motor reaction is a second point of novelty.

Third, better use of the expansion of spent gases is obtained within long stroke cylinders, and while long or arcuate cylinders are not broadly new, however, the device to regulate the degree of compression within the cylinders on the various speeds by the process as outlined is a third point of novelty.

70 I claim:

An internal combustion engine operating on the principle of a gyroscope including, a housing in the shape of a flattened sphere having peripheral exhaust ports and supported in a fixed position, a motor functioning as a

7 flywheel mounted within the housing and having substantially upper and lower side walls and cylinders formed in the periphery thereof at substantially diametrically opposite locations, intake and exhaust valves for said cylinders, a gear box at the underside of the housing, a primary shaft having its lower end journaled in the gear box and having its upper portion extending through the motor and constituting the axis of rotation thereof, a hub fixed to the bottom wall of the motor housing and rotatable about said shaft, a driving gear on said hub, a primary gear keyed to said shaft between said upper and lower walls, crank members journaled in said upper and lower walls, pinions on said crank members meshing with said primary gear, a Z-shaped lever having piston rod portions provided at their outer ends, pistons operating with said cylinders, the medial shank portion of said lever being freely rotatable about said shaft, links at opposite sides of the shaft and connecting said lever with

5 said crank elements, valve actuating cams on said primary shaft for respectively operating the intake and exhaust valves, bell-crank type valve actuators adapted for engagement by said cams and in turn alternatively actuating said valves, a bevel gear on said primary shaft meshing with a bevel gear on a workshaft journaled in said gear box, a second bevel gear meshing with the driving gear on said hub and having a workshaft journaled in the gear box, means for supplying fuel to the motor, 10 governor means for controlling the cam, controlling the intake valves, and ignition means for each cylinder.
